United States Patent Office

Des. 180,799
Patented Aug. 13, 1957

180,799

CALENDAR STAND OR SIMILAR ARTICLE

Carlyle N. Montanye, Glyndon, Md.

Application March 11, 1957, Serial No. 45,200

Term of patent 14 years

(Cl. D74—5)

FIG. 1

FIG. 2

FIG. 3

FIG. 5

FIG. 4

Fig. 1 is a front elevation of a calendar stand, showing my new design;

Fig. 2 is a top plan view;

Fig. 3 is a horizontal sectional view taken on the line 3—3 of Fig. 1;

Fig. 4 is an end or side elevation; and

Fig. 5 is an enlarged vertical sectional view taken on the line 5—5 of Fig. 1.

I claim:

The ornamental design for a calendar stand or similar article, as shown.
